ANIMAL TOY OR SIMILAR ARTICLE

Alan Reed, Beverly Hills, Calif.

Application July 25, 1955, Serial No. 37,122

Term of patent 14 years

(Cl. D34—2)

Fig. 1

Fig. 2

Fig. 3

Figure 1 is a front perspective view of an animal toy or similar article showing my new design;

I claim:

The ornamental design for an animal toy or similar article, as shown.
